BUFFING MACHINE

Filed Nov. 20, 1928

UNITED STATES PATENT OFFICE

EDWARD F. HODGKINS, OF BEVERLY, MASSACHUSETTS, ASSIGNOR TO UNITED SHOE MACHINERY CORPORATION, OF PATERSON, NEW JERSEY, A CORPORATION OF NEW JERSEY

BUFFING MACHINE

Application filed November 20, 1928. Serial No. 320,585.

This invention relates to buffing machines, and is herein illustrated with particular reference to its application to buffing machines wherein the abrading element is carried upon an elongated inflatable casing of the type illustrated in United States Letters Patent No. 1,575,686, granted March 9, 1926, upon my application, such machines being especially adapted for buffing or scouring the breasts of Louis heels.

In machines of the type above mentioned the inflatable casing, which carries on it an abrasive cover, is mounted upon a hollow, driven spindle through which air under pressure is supplied to inflate the casing. The casing is tubular in form, having an open inner end to receive the spindle over which it is drawn. As the material of the casing is yieldable, such as rubber or rubber composition, it is desirable to secure each end of the casing to the spindle, not only to prevent twisting of the casing with respect to the spindle due to the frictional drag of the work against which the abrasive covered casing is rotated, but also to prevent longitudinal displacement of either end of the casing with respect to the spindle, which displacement, if not prevented, might result from the tendency of the casing to elongate under inflation.

One of the objects of this invention is to provide an improved means of securing each end of an inflatable casing of the type referred to to its spindle in such a manner as to overcome any tendency on the part of the casing to twist or to be displaced longitudinally with respect to the spindle.

In accordance with this object, one feature of the invention resides in improved means for securing the outer end of a casing from twisting relatively to a spindle on which it is mounted. In the illustrated organization, the rotary spindle has at its outer end a recess of non-circular cross-section, and the outer end of the resilient casing carried upon the spindle is provided with a rigid member bonded to the rubber casing and having a portion of a cross-section complementary to the noncircular cross-section of the recess in the spindle and adapted to enter the recess to prevent twisting of the casing with respect

to the spindle. The recess in the spindle constitutes a socket, which, in the illustrated spindle, is square. The socket and the shank of the rigid member to which the casing is bonded together constitute a non-rotary coupling for preventing relative twist between the outer end of the casing and the spindle.

The invention provides also, as a further feature, novel means for preventing both wear and distortion of the outer end of the casing under the pressure of work applied to the abrasive cover, thereby to avoid loosening of the bond between the above-mentioned rigid member and the casing. To this end, a rigid cup is provided surrounding the lower or outer end of the casing, which affords additional bonding surface for the pad, as well as preventing wear and distortion. As illustrated, the rigid polygonal coupling member referred to above is both fixedly secured to the cup and is embedded in the casing, thereby providing a positive interlocking bond between itself and the material of the pad in which it is embedded.

Still another feature of the invention resides in novel means to prevent a casing of the type above-mentioned from elongating under pressure, and thus to prevent longitudinal displacement between the outer end of the casing and the spindle. In the illustrated construction, the means for preventing such longitudinal displacement includes a spring latch extending within the spindle from the outer end of the casing into an opening in the spindle wall, the opening being located at a point adjacent to the open end of the casing to render the latch accessible.

The above described tubular casing may be formed by molding the material of the casing in a longitudinally split mold, the central hollow portion of the casing being formed by a core. The end of the core adjacent to the open end of the casing may be supported by the mold; but it is apparent that unless some positive support is provided for the other end of the core, the unsupported end of the core might, in the process of filling the mold and kneading the unvulcanized rubber, be forced out of alignment with the mold, and the re-

sulting casing might be of uneven thickness. A further feature of the invention, therefore, resides in the provision of a rigid member which, in the finished casing, is secured to and covers one end of the casing, and which is constructed and arranged to support one end of the core during the molding of the casing, the rigid member having a cylindrical portion which surrounds an end of the casing. 5
10 The above-described rigid cup and the coupling member secured thereto may constitute such a means for supporting and centering the core, the latter being provided with a socket of complementary cross section to that of the shank of the coupling member to enable the shank of the coupling member to fit into the socket of the core during the process of molding. 15
A further feature of the invention consists 20 in the provision of a readily replaceable member, illustrated as a grommet, which is interposed between the edge of the inner end of the abrasive cover and a collar which clamps the casing to its spindle. The illustrated grommet has a portion surrounding the casing and interposed between the casing and the abrasive cover, and it has also an outwardly extending flange beyond the end of the abrasive cover. This grommet 25 serves to protect the edge of the clamping collar from the abrading action of the edge of the abrasive cover. When it is desired to space the end of the abrasive cover from the casing securing means, a plurality of such 30 grommets may be employed. In such case the additional grommet or grommets serve to prevent bulging of the casing between the edge of the abrasive cover and the casing securing means. 35
40 These and other features of the invention will now be set forth in detail in the accompanying drawing, in which

Fig. 1 is an elevation of the head of a buffing machine embodying the invention in a 45 preferred form;

Fig. 2 is a side elevation of the buffing tool of the machine with parts broken away and in section;

Fig. 3 is a perspective view of the rigid member for preventing twisting of the outer end of the resilient tool casing with respect to the spindle;

Fig. 4 is a side elevation, partly in section, showing the arrangement of the abrasive 55 cover with respect to the resilient tool casing; and

Fig. 5 is a fragmentary perspective view showing a detaching tool in the operation of detaching the resilient casing from the 60 spindle.

The illustrated buffing machine, which is a Naumkeag machine of the type disclosed in the above-mentioned Letters Patent, is provided with a laterally extending head 10 65 which carries bearings 12 and 14 within

which is supported for rotation a hollow spindle 16. Air is supplied to the spindle 16 through a passage 18, and a pulley 20 is provided between the bearings 12 and 14 to rotate the spindle 16. A portion of the spindle 70 16 below the lower bearing 12 and spaced from the end of the spindle is externally threaded at 22. The lower end of the spindle 16 is recessed to provide a socket 24 of polygonal cross-section, shown in the illustrated spindle as square. A suitable aperture 26 is provided in the lateral walls of the spindle 16, for a purpose later to be explained. 75

A resilient inflatable buffing tool 28, having an abrasive cover, is carried upon the rotatably driven spindle 16. The tool 28 is of the roll type, the illustrated tool being in the form of a cylindrical roll, which form is especially adapted to be used for buffing or scouring the breasts of Louis heels and also for buffing the scallop which is provided in some heels of this type. The curvature of the breast of a Louis heel is such that it can be effectively buffed by the use of a cylindrical roll of relatively small diameter, an inch or less, for example. If such a roll is mounted so that one end is free for presentation of the work, it may also be used for buffing the scallop in the lower end of the breast of the heel. As the spindle 16 is rotated, the frictional drag of the work, acting through the abrasive cover upon the rotating tool, tends to twist the latter relatively to the spindle. The tool, being inflated with compressed air, tends to expand in all directions and therefore to elongate, the ends of the tool thus being subject to longitudinal displacement with respect to the spindle. It is accordingly desirable to provide a tool which is adapted at both ends to be secured to the spindle so as to prevent both relative twist and longitudinal movement. 80 85 90 95 100 105 110 115 120 125 130 135 140 145 150

The illustrated buffing tool comprises a hollow cylindrical pad or casing 30 of resilient material, such as rubber or rubber composition hereinafter termed "rubber", one end of which is molded and vulcanized into a rigid hollow member in the form of a cup-shaped holding device 32, the function of which will presently be described. The cup-shaped device 32 comprises a metal cup having a cylindrical side wall 34 and a disk-shaped bottom wall 36, in combination with a rigid metallic member consisting of upper and lower disks 38 and 40 respectively, arranged in parallel and coaxial relation, the lower disk 40 resting flat against the inner surface of the bottom wall 36, being coaxial therewith and centrally riveted thereto at 42. The disks 38 and 40 are connected by a central or axial rod 44 and by a plurality of rods 46 parallel to the rod 44 and arranged on the circumference of a circle concentric with the 145 150 155 160 165 170 175 180 185 190 195 200

axis of the rod 44, the upper surface of the upper disk 38 having an axially extending shank 48 of polygonal cross-section, shown in the illustrated device as square, which is 5 complementary to the socket 24 and which is adapted to form a non-rotary coupling with the socket 24. The rubber of the casing 30 during its manufacture being molded into the space within the cylindrical wall 34 and 10 about the rods 44 and 46, and being vulcanized in the process of molding, as will hereinafter be explained, adheres to the inner surface of the wall 34 and to the respective inner surfaces of the disks 38 and 40, as well 15 as to the rods 44 and 46, the bond between the rubber and the device 32 being not merely adhesive, but positive and interlocking, for the rods 46 interlock with the rubber positively to prevent twisting or relative rotation, and 20 the inner surfaces of the disks 38 and 40 abut the intervening material of the casing 30. It will be noted that the end of the casing 30 which fits within the device 32 is reduced in diameter by a distance equal to twice the 25 thickness of the cup wall 34. It will also be noted that this end portion is solid, as the central opening which extends from the open end of the tool is terminated by the disk 38. The cylindrical wall 34 not only affords additional bonding surface for the material of 30 the casing 30 which is molded and vulcanized within it, but it also serves to protect the end of the casing from chafing and wear, and from distortion. Without the cylindrical 35 wall 34, the material at the end of the casing 30 might wear down sufficiently to expose the rods 46, thus ceasing to interlock with these rods, while sufficient distortion of the end of the casing might occur under pressure of work applied to the abrasive cover over this point to loosen the bond between the various members of the device 32 and the casing.

The shank 48 is not only non-rotatably engaged with the spindle in the socket 24, but 45 is held against longitudinal movement with respect to the socket. To this end, the free end of the shank 48 is slotted at 50, the slot being bridged by a pin 52 to which is hinged 50 one end of a spring latch member 54, which may be of wire and which is adapted to extend upwardly within the hollow portion of the spindle 16, and by the engagement of its opposite end 56 with the spindle to hold the 55 casing 30 against elongation or stretching. The latch member 54, at a point between its ends and nearer to the end 56 than the end which is hinged to the pin 52, is bent back upon itself, in the manner of a safety-pin, 60 through a closed loop 58 consisting of about two full turns. The loop 58 thus divides the member 54 into two arms of unequal length; and these arms, because of the resilience of the material of which the member 54 is composed, and especially because of the spring 65 action of the loop 58, tend to separate or expand, being confined within the interior of the hollow spindle 16. The end 56 of the member 54 is formed to enter an opening 60 in the wall of the spindle 16. The opening 60 is positioned adjacent to the open end of the casing 30 when the latter is in operative position upon the spindle 16, and the opening 60 may be so positioned, as shown in the illustrated structure, as to be covered by the 70 casing 30. As illustrated, the opening 60 is also positioned in line with one of the corners of the socket 24 to facilitate correctly entering the shank 48 in the socket 24 so as to bring the end 56 of the member 54 into line 75 with the opening 60. The two above-mentioned arms of the member 54 are formed of such length as to bring the end 56 of the member 54 exactly into register with the opening 60 when the shank 48 is correctly and 80 fully entered within the socket 24; and when thus in register, the end 56 will snap into the opening 60 by virtue of the tendency of the two arms of the member 54 to expand, due to the above-mentioned spring action, and 85 will thus hold the lower end of the casing 30, through the holding device 32, against longitudinal movement relative to the spindle 16 due to the tendency of the casing 30 to expand under inflation, or for any other reason. 90

The spindle 16 is of relatively large diameter at its threaded portion 22, and below this portion to the end of the spindle the diameter is reduced to accommodate the casing 30, such reduction of diameter forming a shoulder 95 100 105 110 115 120 125 130

against which the open end of the casing 30 abuts. The casing 30 has an outwardly extending flange 64 surrounding its open end. Threaded on the threaded portion 22 of the spindle 16 is a nut 66 constituting a collar for clamping the flange 64 against the shoulder 62, having an inwardly extending flange 68 and recesses 70 for a wrench. Interposed between the flange 68 and the flange 64 of the casing 30 is an antifriction washer 72 which permits tightening of the collar 66 without twisting the flange 64. To assemble the tool 28 upon the machine, the collar 66 is first unscrewed from the threaded portion 22 and removed from the spindle 16. The casing 30 is then drawn over the end of the spindle 16, the latter extending into the open end of the casing 30, and the casing 30 being held in such position as to bring the end 56 of the latch member 54 into alignment with the opening 60 in the spindle wall. The casing 30 is then pushed up on the spindle 16 as far as it will go; and the shank 48 will enter the socket 24, the end 56 of the latch member 54 will snap into the opening 60, and the open end of the casing 30 will abut the shoulder 62. The collar 66 is then replaced upon the spindle 16, over the tool 28, and is screwed upon the threaded portion 22. Upon tightening the collar 66, the flange 64 of the casing 30

will be compressed between the washer 72 and the shoulder 62, by a clamping pressure directed lengthwise of the spindle 16, and will thus be firmly secured to the spindle 16 against both axial and twisting movement. An annular groove 74 is formed in the shoulder 62, and upon tightening the collar 66, some of the material of the flange 64 is forced into the groove 74, completely filling the groove. This effects an air-tight connection between the open end of the casing 30 and the spindle 16, and at the same time eliminates any possible tendency of this end of the casing to twist relatively to the spindle.

3 The casing 30 is preferably molded and vulcanized in a two-part, longitudinally split mold, the internal shape of which corresponds to the external shape of the casing 30 together with the holding device 32 attached thereto. A central core is employed to provide for the central opening of the casing 30 which accommodates the spindle 16. The end of the core adjacent to the open end of the casing 30 is supported by the adjacent end 25 of the mold. The other end of the core has a socket similar in all respects to the socket 24 of the spindle 16, and the shank 48 of the holding device 32 is first inserted into the socket of the core as far as permitted by the flange 38. The cylindrical or cup wall 34 of the cup-shaped device 32 exactly fits the interior of the mold, having the same cross-section, and thus, through the shank 48, positively supports and centers the end of the 30 core. The open space within the mold is then filled with the unvulcanized rubber which is to be made into the casing 30, and this material is vulcanized in the ordinary way to bring it to a permanent set. The material which fills the cup-like portion of the device 32 may be of different composition from that which is to form the body of the casing 30, so as to render the solid end of the casing 30 somewhat harder and firmer than that portion which is hollow and subject to inflation, to enable this end portion better to withstand the supporting and driving stress introduced into the casing 30 through the device 32 at this point. The cylindrical or cup wall 34 is found to be of very great advantage in the process of molding, for, as above pointed out, it affords a support for the end of the core. If this end of the core were not supported, it would be likely, in the process of kneading and molding the rubber or composition, to be forced out of exact alinement with the axis of the mold, and the result would be an unbalanced casing, thicker on one side than the other. The external side wall of the casing 30 and the exterior of the cup wall 34 are of equal diameter, in cross-section, at their line of contact, and they form a continuous surface which, in the illustrated tool, is cylindrical.

65 A cover 76 of abrasive material, such as

emery paper, having its overlapping ends glued or otherwise secured together to form a cylinder of slightly greater diameter than that of the uninflated casing 30, is carried upon the casing. When air under pressure is admitted through the passage 18 to the interior of the hollow spindle 16, some of the air passes out through the aperture 26 and expands the casing 30, causing it to grip the interior wall of the cylindrical cover 76 and to hold the cover firmly in frictional engagement. The cushion of air between the casing 30 and the spindle 16 insures a yielding action of the abrasive cover 76 upon the work. While the pneumatic cushion thus provided throughout the greater part of the length of the tool does not extend completely to the end of the tool, because the hollow portion of the casing 30 terminates at the upper surface of the disk 38, nevertheless a cushioning effect is obtained even at the very end of the tool by reason of the fact that the diameter of the abrasive cover is slightly larger than the diameter of the solid end of the tool, and is supported at this point by its inherent stiffness, which is assisted somewhat by the action of centrifugal force, and not directly by the end portion of the tool.

The abrasive cover 76 has been found, during operation, to have a tendency to work upward. In order to prevent the rough upper edge of the abrasive cover 76 from wearing or cutting an annular groove in the lower face of the clamping collar 66, a grommet 78 is employed. The grommet 78 may be formed of sheet brass, and consists of a cylindrical portion which is interposed between the casing 30 and the cover 76, and an outwardly extending flange 80 which is interposed between the upper edge of the cover 76 and the lower face of the clamping nut 66. It may be noted that the grommet 78 affords a cheap and readily replaceable means for protecting the lower face of the clamping nut 66.

It is desirable, under certain conditions of operation, to have the lower end of the abrasive cover 76 extend below the end of the tool upon which it is carried. In this case the overhanging end 82 (Figs. 2 and 4) of the abrasive cover 76 is supported by its inherent stiffness and by centrifugal force, with no material backing, thus affording an especially soft cushioning effect of the abrasive material against the work. The overhang of the end 82 may be obtained, in the first instance, by making the cover 76 of sufficient length to extend from the lower face of the clamping nut 66 to a point below the end of the tool. As the abrasive material at the end 82 wears away, it is in the interest of economy to cut off the end of the cover 76 and to move the cover down to present a fresh portion to the work, rather than to provide a new cover. When the cover 76 is thus moved down, an additional grommet 84, similar in all respects

70

80

85

90

95

100

105

110

115

120

125

130

to the first grommet 78, is employed. The flange 80 of the grommet 84 abuts the upper edge of the cover 76 and prevents the latter from working upward, while the first grommet 78 acts as a stop or spacer member to prevent the second grommet 84 from working upward, and also serves to prevent the otherwise exposed portion of the casing 30 from bulging. But for the grommets 78 and 84, the exposed portion of the casing 30 would be likely to bulge over the upper edge of the abrasive cover 76, and might be injured by contact with this rough upper edge. As the overhanging end 82 is used up, the cover 76 may thus be moved down again and further grommets added.

The spring latch member 54 may be disengaged from the spindle 16 by the insertion of a blunt tool into the opening 60 to force back the end 56, whereupon the casing 30 may be withdrawn. To accomplish this, the collar 66 is first unscrewed and removed from the spindle 16. While the opening 60 is covered by the casing 30 when the latter is in operative position, the casing 30, because of its flexibility, can easily be forced down the short distance necessary to expose the opening 60 and to render the end 56 accessible to the disengaging tool.

50 In Fig. 5 is shown a tool of novel construction for disengaging the spring latch member 54 from the spindle 16. This disengaging tool consists of a forked member having a handle portion 86 and a pair of flat prongs 88 which are adapted to straddle the spindle 16. A relatively short projection 90 is disposed between the prongs 88 and is adapted to enter the opening 60 to disengage the end 56 of the spring latch member 54. The prongs 88 have flat upper surfaces, both in the same plane, which are held against the shoulder 62 of the spindle 16 while the disengaging tool is thrust forward to bring the projection 90 into disengaging position. The forward edges 92 of the prongs 88 are beveled as shown at 94 to render the prongs wedge-shaped, the beveled portions 94 extending downwardly from the upper surfaces of the prongs 88 to the lower surfaces so as not to destroy the continuity of the upper surfaces. The purpose of the bevels 94 is to force the upper end of the casing 30 down a distance equal to the full thickness of the prongs 88 so as to expose the opening 60. The projection 90 is disposed between the upper and lower surfaces of the prongs 88 at a point where it will register with the opening 60 when the upper surfaces are held against the shoulder 62. A file cut (not shown) on the threads 22 may be employed to mark the position of the opening 60.

In operation, the machine is set in motion and the breast of the heel is presented to the rotating tool 28, the operator applying the heel in a horizontal position and moving it

forward and backward to bring all parts of the breast of the heel into contact with the tool. The curvature of the tool is sufficiently less than that of the breast of the heel to permit access to all parts thereof. If the heel 70 breast is scalloped the operator may then present the shoe in an inverted vertical position and apply the scallop to the tool.

Having thus described my invention, what I claim as new and desire to secure by Letters Patent of the United States is:

1. In a buffering machine, a rotary spindle having at its end a recess of non-circular cross-section, an elongated resilient casing carried upon said spindle, and a rigid member 80 bonded to said casing and having a portion of a cross-section complementary to said non-circular cross-section of said recess and adapted to enter said recess to prevent twisting of said casing with respect to said 85 spindle.

2. In a buffering machine, a rotary spindle having an axially extending socket of polygonal cross-section formed upon its end, an elongated resilient casing carried upon said 90 spindle, and a rigid member bonded to said casing and having a shank portion of a cross-section complementary to the cross-section of said socket and adapted to enter said socket to prevent twisting of said casing with respect to said spindle.

3. In a buffering machine, a rotary spindle having an axially extending square socket formed upon its end, an elongated resilient casing carried upon said spindle, and a rigid 100 member bonded to said casing and having a square shank adapted to enter said socket to prevent twisting of said casing with respect to said spindle.

4. In a buffering machine, a rotary spindle, 105 a resilient inflatable casing mounted on said spindle, and means including a latch secured to said casing for securing said casing to said spindle, said casing having an open end and a closed end and said latch having a portion adjacent to the open end of said casing to render the latch accessible for operation.

5. In a buffering machine, a rotary spindle, a resilient casing mounted on said spindle, means for securing one end of said casing to 115 said spindle, means for preventing relative twisting between the opposite end of said casing and said spindle, and means including a spring latch for preventing relative longitudinal displacement between said opposite end of said casing and said spindle.

6. In a buffering machine, a rotary spindle, a resilient casing mounted on said spindle, means for securing one end of said casing to 125 said spindle, a non-rotary socket connection between the opposite end of said casing and said spindle, and means including a spring latch for preventing relative longitudinal displacement between said opposite end of said casing and said spindle.

7. In a buffing machine, a rotary spindle, a resilient casing having an open end, said spindle extending into said casing through said open end thereof, means for securing said casing at the open end thereof to said spindle to prevent relative longitudinal and rotary displacement between said end of said casing and said spindle; means for preventing relative rotary displacement between the opposite end of said casing and said spindle, and means including a spring latch for preventing longitudinal displacement between said opposite end of said casing and said spindle.
8. In a buffing machine, a rotary hollow spindle having an opening in its wall, a resilient casing having an open end, said spindle extending into said casing through said open end thereof, means for securing said casing at a point adjacent to the open end thereof to said spindle, and means including a spring latch engageable with the wall of the spindle in said opening for securing the opposite end of said casing to said spindle, said spring latch extending within said spindle from said opposite end of said casing to said opening, and said opening being located at a point adjacent to said open end of said casing to render said latch accessible through said opening.
9. In a buffing machine, a hollow rotary spindle having an opening in its wall, a resilient casing having an open end, said spindle extending into said casing through said open end thereof and said opening in the wall of said spindle being adjacent to said open end of said casing, means for securing said casing at the open end thereof to said spindle to prevent relative longitudinal and rotary displacement between said open end of said casing and said spindle, means including a socket connection for preventing relative rotary displacement between the opposite end of said casing and said spindle, and spring means secured to said opposite end of said casing and extending within said hollow spindle to said opening in the wall thereof, said spring means being engageable with said opening to prevent longitudinal displacement of said opposite end of said casing with respect to said spindle.
10. In a buffing machine, a rotary spindle, a carrier for an abrasive cover, means for securing said carrier to said spindle, an abrasive cover mounted on said carrier, and a replaceable member interposed between an edge of said abrasive cover and said carrier securing means to protect the latter from contact with said edge of said cover.
11. In a buffing machine, a rotary spindle, an elongated inflatable casing, means for securing said casing to said spindle, an abrasive cover surrounding said casing, and a replaceable member interposed between the edge of one end of said abrasive cover and said casing securing means to protect the latter from contact with said edge of said cover.
12. In a buffing machine, a rotary spindle, an elongated inflatable casing mounted on said spindle, an abrasive cover surrounding said casing, and a grommet having a portion surrounding said casing and interposed between said casing and said cover adjacent to one end of said cover, said grommet having an outwardly extending flange beyond said end of said cover.
13. In a buffing machine, a rotary spindle, an elongated inflatable casing, means for securing said casing on said spindle, an abrasive cover surrounding said casing, and means interposed between the edge of one end of said abrasive cover and said casing securing means, said interposed means being adapted to space said end of said cover from said casing securing means and to prevent bulging of said casing between said edge of said cover and said casing securing means.
14. In a buffing machine, a rotary spindle, an elongated inflatable casing, means for securing said casing on said spindle, an abrasive cover surrounding said casing, one end of said cover extending beyond one end of said casing, and a plurality of grommets surrounding said casing and interposed between the opposite end of said cover and said casing securing means to space said opposite end of said cover from said casing securing means and to prevent bulging of said cover between said opposite end of said cover and said casing securing means.
15. In a buffing machine, rotary hollow spindle having a shoulder spaced from the end of the spindle and having an opening in the wall of said spindle between said shoulder and said end, and also having a non-circular socket in said end, said shoulder, said opening and said socket being adapted to cooperate with corresponding parts of a buffing tool to maintain said tool on said spindle.
16. In a buffing machine, a rotary hollow spindle having an opening in its wall spaced from the end of said spindle and having a square socket at its end, said opening and said socket being adapted to cooperate with corresponding parts of a buffing tool to maintain said tool on said spindle in such position as to enable said corresponding part of said tool to register with said opening.
17. In a buffing tool, in combination, a rigid device having a cup-shaped portion and a portion adapted to be connected with a rotary driven member, and a yieldable casing having one end carried within said cup-shaped portion, the remaining portion of said casing extending beyond the open end of said cup-shaped portion and said device

and the end of the casing within the cup-shaped portion of said device being interlocked.

18. In a buffing tool, in combination, a rigid device having a cup-shaped portion and a portion adapted to be connected with a rotary driven member, and a yieldable casing having one end carried within said cup-shaped portion, the remaining portion of said casing extending beyond the open end of said cup-shaped portion and the end of the casing within the cup-shaped portion of said device being bonded to said device.

19. In a buffing tool, a tubular molded and vulcanized rubber casing adapted to carry an abrasive cover, and a rigid member having a cylindrical portion surrounding an end of said casing to protect said end against wear, said rigid member being secured to said end of said casing by interlocking with the material of said casing, said rigid member being constructed and arranged to support one end of a core which forms the central hollow of said casing in the process of molding and vulcanizing the latter.

20. In a buffing tool, in combination, a tubular casing of yieldable material having an outer end and an open inner end to permit the casing to be drawn over a hollow spindle, a latch within said casing adapted to enter and to engage the hollow spindle, and means for securing said latch to said outer end of said casing.

21. In a buffing tool, in combination, a tubular casing of yieldable material having an outer end and an open inner end to permit the casing to be drawn over a hollow spindle, a latch within the casing adapted to enter the hollow spindle, said latch having a pair of arms resiliently tending to expand against the inside wall of the spindle, one of said arms being constructed and arranged to engage an opening in the wall of the spindle, and means for securing one of said arms to said outer end of said casing.

22. In a buffing machine, a rotary spindle constructed and arranged to be engaged by a latch at a point spaced from the ends of the spindle, a resilient casing mounted on said spindle, and a latch secured to said casing and engageable with said spindle at said point for securing said casing to said spindle.

23. In a buffing machine, a rotary spindle, a resilient casing mounted on said spindle, said casing having an open end into which the spindle extends and having its opposite end closed, and a spring latch secured to said casing for securing said casing to said spindle at a point adjacent to the open end of said spindle.

In testimony wherof I have signed my name to this specification.

EDWARD F. HODGKINS.
